To all whom it may concern:

Be it known that I, FRANK J. As shown in the drawing, the leading and material feature of my design consists of a series of parts. The leg 1 is convex, with broad scroll top, with carved front at 6, with 15 beaded and carved edge at 5, with a beaded

molding at 8, and a top 2, with a side panel 3, with scalloped cross-pieces 4, with a pendent half-circle 7, with arms converging to the center of the circle.

Having described my invention, what I claim as new, and desire to secure by Letters Patent, is—

The design for a footstool as herein shown and described.

In testimony whereof I affix my signature 25 in presence of two witnesses.

FRANK J. HEGMAN.
